UNITED STATES PATENT OFFICE.

CARL EDGAR MYERS, OF FRANKFORT, NEW YORK.

AIRSHIP.

1,078,455.

Specification of Letters Patent.

Patented Nov. 11, 1913.

Application filed April 8, 1908. Serial No. 425,942.

To all whom it may concern:

Be it known that I, CARL E. MYERS, a citizen of the United States, and a resident of Frankfort, in the county of Herkimer and State of New York, have invented a new and Improved Airship, of which the following is a full, clear, and exact description.

This invention relates to airships and especially to such as employ gas bags to give them buoyancy in the air.

The invention contemplates the use of an explosion engine for propelling the airship, and one object is to provide an arrangement whereby the exhaust gases from the engine may pass into the gas bag to affect the buoyancy or equilibrium thereof.

A further object of the invention is to provide improved steering devices for the airship.

20 A further object of the invention is to provide improved means for insuring that the gas bag will maintain its normal shape at its ends under heavy wind pressures.

25 A further object of the invention is to provide an arrangement whereby the gas contained in the gas bag may be used as a fuel in the engine or motor.

The invention consists in the construction and combination of parts to be more fully 30 described hereinafter and particularly set forth in the claims.

Reference is to be had to the accompanying drawings forming a part of this specification, in which similar characters of reference indicate corresponding parts in all the 35 figures.

Figure 1 is a longitudinal section through the gas bag of an air ship constructed according to my invention; Fig. 2 is a section 40 through the lower portion of the gas bag upon an enlarged scale; this view is diagrammatic, and illustrates the relation between the motor or gas engine and the gas bag; in this view certain parts are shown in elevation and others are broken away; Fig. 45 3 is a perspective showing the under side of the upper wall of the gas bag, and illustrating a valve and the novel means for controlling the same; and Fig. 4 is a view similar to Fig. 3, but representing a ripping strip which may be removed in order to allow the gas within the bag to escape suddenly so that the air ship may sink to the ground; this view is for the purpose of illustrating the novel means for operating the 50 55 ripping strip.

Referring more particularly to the parts, and especially to Fig. 1, 1 represents the gas bag, which is of elongated form, as shown, and formed with a point 2 at the front and 60 a point 3 at the rear. The body of the balloon is of circular cross section, and it is formed of some suitable light textile material. At the points 2 and 3, that is, at the forward and rear ends of the gas bag, the 65 form is maintained by means of gas-inflated bulbs or heads 4, having substantially the form shown. These bulbs may be flexible or of non-collapsible material; they are substantially spherical at their inner or 70 butt ends, and pointed at their outer ends, so as to give the desired shape to the ends of the gas bag. The pointed ends of the bulbs lie against the inner side of the 75 wall of the gas bag at this part, as shown.

On its lower side the gas bag is provided with ballonnets or inner gas-bags 5 and 6; one of these gas bags is located at the rear of the middle line of the gas-bag, and the other just forward of this line. These bags are 80 formed of some suitable collapsible textile material, and each ballonet is provided with a safety valve 7 through which the contained gas may escape to the outer air if the pressure rises sufficiently. Between the bags 85 5 and 6 the wall of the gas-bag is provided on its under side with a similar safety valve 8, which allows the gas from the interior of the gas bag or main compartment to escape into the outer air. This valve is substantially 90 similar in its construction and function to the valves 7.

Beneath the gas bag 1, I provide an elongated car or body 9 which contains the operator of the air ship, and the machinery. 95 This car is supported from the gas bag in any suitable manner, not shown. Within the car I provide a motor 10 having the form of an engine employing an explosive fuel such as gasolene. This engine is provided with a fly-wheel or balance wheel 11, which operates as a pulley to drive a blower or fan 12 through the medium of a suitable belt 13. This blower 12 has a delivery pipe 14 having two branches 15 and 16; in other 100 words, a Y pipe is used. In the branch 15 a valve or damper 17 is provided for cutting off the flow of current through the branch, and a similar valve or damper 18 is provided in the other branch 16. The 110 fan 12 is provided with an intake 19 which leads from a muffler 20, taking the exhaust

gas from the cylinder of the engine 10. This muffler has an outlet 21, to the atmosphere. In addition to the intake 19, the fan is similarly provided with an intake 22 for free air. The intake 19 is provided with a valve or damper 23, and a similar valve or damper 24 is provided in the intake 22. Likewise, a damper 25 is provided in the outlet 21 from the muffler.

10 In addition to its ordinary liquid fuel supply, I provide means for driving the gas engine 10 by means of the gas contained in and forced by pressure from the gas-bag 1, which gas would be of an explosive nature. 15 For this purpose, I connect the interior of the gas-bag with the cylinder of the engine at the proper point by means of a tube 26, as shown.

Within the car or body 9 there are provided screw shafts 27^a, 27^b, which extend 20 beyond the ends of the body 9, and are provided with propellers 28, 29, as shown. Along the body 9 also extend independent rudder-shafts 30^a, 30^b, in tight bearings 9^a, 25 permitting such rudder-shafts to slide along or rotate within said supports, but not movable by the air pressure. Attached to the outer extremities of the rudder-shafts are aeroplanes 30, 31, for steering. The partial 30 rotation of the rudder-shafts with the cross-arms will place the cross-arms and aeroplanes in any position between horizontal and vertical, thus giving the double functions of aeroplanes and rudders combined. 35 In addition to this balancing effect by wind pressure acting on the vanes 30 and 31, the shafts which carry them act as counter-weights, for they may be slid longitudinally in their bearings 9^a; evidently if the shaft 40 30^a is slid forwardly with the vane 30 it will tend to depress the front end of the airship, and vice versa. In using the vanes 30 and 31 as counterweights simply, they are placed nearly in a vertical plane so that they do 45 not have any buoyant effect. Changing the position of these vanes longitudinally also changes their effect on the balancing of the airship, for evidently the steering effect will be greater when the vane is moved nearer to the end of the airship.

50 On its upper side the wall of the gas-bag near its middle point is provided with a vent or opening 32, which is normally closed by a valve or flap 33 on the inner side of the wall. This flap or valve may be opened 55 when desired by means of a depending cord 34 which passes through the bottom wall of the gas-bag and is provided with a ring 35 hanging within easy reach of the operator within the car. To the cord 34 near its point of attachment to the valve 33, a spring or elastic cord 36 is attached, the upper end of which spring is attached to the wall of the gas-bag, as shown. In this way the 60 65 cord 34 is made to hang in a loop near the

valve. From this arrangement it will be evident that a slight pull upon the cord 34 will not open the valve, and it will be necessary, in order to open the valve, to give the cord sufficient pull to extend the spring 36 until all of the looped cord is taken up. This spring 36 and its coöperating parts I consider a safety device, as it prevents the valve from being opened accidentally. A similar safety device 37 is provided near the spring 36, a cord 38, in this case, being attached to a ripping strip 39 which covers a large vent 40 in the wall of the balloon at this point. This cord 38 passes through the bottom of the balloon body, and is also provided with a ring 41 near the car. The construction of this safety device and its arrangement with respect to the valve 37 and the strip 39, are very clearly illustrated in Figs. 3 and 4. The valve 33 is normally held closed by a spring 42, as shown.

In the operation of the airship, it should be understood that the non-collapsible or high-pressure gas-inflated bulbs 4 at the front and rear maintain the pointed form of the gas bag against the wind pressure. The gas bag is inflated with an explosive gas such as hydrogen or some similar explosive mixture of gases which will be lighter than air. By means of the ballonnets 5 and 6, 95 the longitudinal equilibrium of the gas bag may be maintained. This is accomplished, as illustrated in Fig. 2, by controlling the flow of gas or air through the ballonnets. In Fig. 2, the interior of the ballonet 6 100 is opened to communication with the gas coming from the muffler. In this way the hot gases of the engine are advanced by the fan or by force of exhaust pressure into the ballonet; hence, the ballonet 6 will become 105 inflated and increase the buoyancy of the right or forward end of the air ship. An opposite effect could be produced by forcing cold air into the ballonet 6 instead of a hot gas from the engine. This is accomplished by closing the damper 23, opening the damper 25 and the damper 24, whereupon free air will enter the intake 22 and be passed up to the ballonet 6 by the fan. From this arrangement, evidently either of 110 the ballonnets 5 or 6 may be charged with hot gas or cold air as desired, and either of them may be opened to the atmosphere to deflate them when desired.

115 It is found in practice that the consumption of the fuel materially diminishes the weight which is to be carried by the gas bag, and in order to compensate for this loss of weight, I have provided the arrangement for using a part of the gas contained in the 120 gas bag for propelling the engine. In this way the buoyancy of the entire air ship may be maintained substantially constant, and, furthermore, when the flight of the air ship 125 is coming to an end, the gas within the bag 130

may be partially consumed in order to supply the engine. In this way the buoyancy of the air ship is subtracted from in order that the ship will sink slowly to the earth, 5 and at the same time, the gas withdrawn from the bag is used as a fuel for the engine. When it is desired to allow the gas within the gas bag to escape in small quantities, the cord 34 is pulled by the operator within 10 the car, opening the valve 33 in the manner above described. If it is desired to allow the gas within the gas bag to escape in large quantities so that the air ship will sink quickly to the earth, the cord 38 is pulled 15 which will rip off the ripping strip 39 and open a comparatively large opening or vent 40.

The bulbs or heads 4 in the ends of the gas bag are permanently filled with a light gas 20 of greater pressure than that adjacent, so as to resist the external pressure.

Special attention is called to the fact that the temperature of the gas contained in the ballonnets is under control, that is, the temperature 25 may be high or low, as desired. Of course, the buoyancy of the ballonet is higher with the higher temperature. This renders the ballonnets useful in maintaining the equilibrium or balance of the gas bag.

Having thus described my invention, I claim as new and desire to secure by Letters Patent:

1. An airship having a gas bag tapered at each end, and provided with non-collapsible heads likewise tapered to points, and of 35 spherical form at the inner parts, said heads serving to brace and reinforce said gas bag at the extremities, and forming stiffeners for the wall of the gas bag near the ends thereof.

2. In an airship a gas bag, a body carried 40 thereby, and an aeroplane rudder carried by said body and rotatable into a plurality of positions, said rudder being freely movable bodily in the direction of the length of its axis of rotation to affect gravitationally the 45 equilibrium of the airship.

3. In an airship a gas bag, a body supported thereby, shafts carried by said body, one at each side of the center of balance of the airship, said shafts being rotatable and 50 being freely movable bodily in the directions of their lengths to affect gravitationally, the equilibrium of the ship, said shafts having means permitting their manipulation, and aeroplane rudders rigidly connected with 55 said shafts.

In testimony whereof I have signed my name to this specification in the presence of two subscribing witnesses.
